UNITED STATES PATENT OFFICE

2,475,021

T-SQUARE HOLDING CLIP

John P. Gibbons, Chicago, and William P.
McGuire, Arlington Heights, Ill.

Application January 19, 1946, Serial No. 642,236

2 Claims. (Cl. 33—80)

1

This invention relates to drafting implements and particularly to a device for holding the head of a T-square in firm contact with the guiding edge of a drawing board.

The main objects of this invention are to provide a simple and improved means for holding the head of a T-square against the guiding edge of a drawing board while permitting free movement of the blade to various parallel positions; to provide an improved form of spring clip adapted to be readily removed or applied to the free end of a T-square; to provide a form of such clip which will hold the square gently but positively in the desired relation to the board no matter at what angle the drawing board is tilted; and to provide a spring clip of this kind that is adaptable to fit onto any width of T-square blade and which is inexpensive and simple to manufacture.

Several illustrative embodiments of this invention are shown in the accompanying drawings, in which:

Figure 1 is a top view of a drawing board and T-square equipped with a holding clip according to this invention.

Fig. 2 is a perspective view showing one form of the clip in its relation to the T-square blade and drawing board.

Fig. 3 is a similar perspective view of a modified form of the clip.

Fig. 4 is a similar perspective view of a further modification of the clip.

As shown in the drawings, the T-square may comprise the usual thin blade 1 and head 2, secured in fixed relation to each other by screws 3. The inside edge of the head is adapted to bear against and slide along one edge 4.1 of a drawing board 4 and hold the blade at right-angles to such edge.

In the form shown in Figs. 1 and 2, the device or clip is made up of a flat body plate 5 formed to fit under the T-square blade. A tongue 6, which is a continuation of the body plate, is bent back upon itself to form an open-ended resilient clamp adapted to grasp the broadside of the T-square blade. The tongue 6 is normally urged toward the body plate 5. An arm 7 integral with the body plate 5 and depending at right-angles therefrom has a tongue 8, positioned to extend along and bear upon the edge 4.2 of the drawing board. The extending tongue 8 is bent inwardly upon itself to form a resilient loop which is positioned to bear against the edge 4.2 of the drawing board. In use the body plate 5 and the tongue 6 are snapped onto the broadside of the free end

2

of the T-square blade and positioned thereon so that the arm 7 rests flush against the edge 4.2 of the drawing board while the tongue 8 bears resiliently against this edge, which is remote from the head of the T-square, thus exerting a pull on the head that is directed along the blade of the T-square.

In the modified form illustrated in Fig. 3, the clip comprises a flat body plate 9, formed to fit under the T-square blade. A substantially U-shaped fixed jaw 10 is formed at one end of the body plate by a part that extends upwardly then inwardly. At the opposite end of plate 9 a tongue-like extension is bent upwardly then downwardly to form a vertically extending spring loop 11, the lower end of which is bent to form a resilient jaw 12 bearing toward the jaw 10 having vertically extending lip 13 to facilitate the release of the jaws.

An arm 14 depends at right-angles from the body plate 9 and may be formed by bending a portion of the plate downwardly at a 90° angle. A tongue 15, extending sidewise from the arm 14 is bent inwardly in suitable form to bear resiliently against the edge of the drawing board.

In use the body plate 9 is slid under the free end of the T-square, the spring tongue loop 11 and the finger 13 being grasped between the thumb and index finger to exert pressure to separate the jaws and allow the jaws to slide freely along the edges of the T-square blade. The jaws are slid along the blade edge until the flat arm 14 abuts firmly against the drawing board whereupon pressure is released to allow the jaws to firmly grip the T-square blade. The tongue 15 will then bear resiliently against the edge of the drawing board to hold the T-square head in firm parallel engagement with the opposite edge of the board.

In the further modified form shown in Fig. 4, the clip comprises a body plate bent upon itself to form a U-shaped clip having portions 16 and 17 for respectively engaging the bottom and top faces of the T-square and being slotted at 18 within its margins to form a centrally located spring tongue which is bent downward in an ogee curve so as to bear against the edge of the drawing board as shown.

In use the clip is fitted onto the free end of the T-square blade so as to grip the blade and to position the spring tongue 19 to bear resiliently on the edge of the drawing board to hold the head of the T-square in firm engagement with the opposite edge of the board.

All of the above-described clips may be stamped

from spring sheet stock, being first cut to shape and then bent in the forms herein-described. As all of the clips are designed to bear against one edge of the drawing board, it will be apparent that the entire T-square and clip may be moved from position to position by grasping the head of the T-square in one hand and the clip in the other hand, exerting pressure in the desired direction, which will cause the T-square head and the clip to slide along their respective edges. When the pressure is released, the spring clip secures the T-square in the desired position.

Although we have shown and described several illustrative embodiments of the invention, it will be understood that various details of the structures shown may be altered or omitted without departing from the invention as defined by the following claims.

We claim:

1. A device for holding a T-square on a drawing board, comprising a body plate of resilient sheet material shaped to form a tongue continuing from said plate and bent back upon said plate to form with the plate an open-ended resilient clamp adapted to embrace one longitudinal edge of the T-square blade and grasp the broad faces of said blade and an arm depending at right angles from said body plate and disposed generally parallel to said tongue, said arm having a resilient tongue bent to bear against the edge of a drawing board on which the T-square may be mounted remote from the head of the T-square and to coact with said clamp to exert a pull on the head directed along the blade of the T-square.

2. A device for holding a T-square on a draw-

ing board, comprising a body plate of resilient sheet material shaped to form a tongue continuing from said plate and bent back upon said plate to form with the plate an open-ended resilient clamp adapted to embrace one longitudinal edge of the T-square blade and grasp the broad faces of said blade and an arm depending at right angles from said body plate and disposed generally parallel to said tongue, said arm having a tongue bent inwardly upon itself to form a resilient loop adapted to bear against the edge of a drawing board on which the T-square may be mounted remote from the head of the T-square and coacting with said clamp to exert a longitudinal pull on the T-square blade in the direction away from the head.

JOHN P. GIBBONS.
